DAVID M. SMITH,
INVENTOR,
By *R. Wright*
ATTY.

UNITED STATES PATENT OFFICE.

DAVID M. SMITH, OF GARDEN HOME, OREGON, ASSIGNOR OF ONE-HALF TO H. B. DYER,
OF PORTLAND, OREGON.

VICE.

1,332,364.

Specification of Letters Patent.

Patented Mar. 2, 1920.

Application filed August 28, 1919. Serial No. 320,365.

To all whom it may concern:

Be it known that I, DAVID M. SMITH, a citizen of the United States, residing at Garden Home, in the county of Washington 5 and State of Oregon, have invented a new and useful Improvement in Vises, of which the following is a specification, reference being had to the accompanying drawings.

My invention relates to a class of devices 10 for securing material upon which a workman is operating.

The object of my invention is to provide a vise which can be released in a manner to operate the same in shorter time than those 15 of common type, also to permit the jaws to be adjusted to an efficient gripping position with a minimum movement of parts. I attain these objects, as well as other advantages, by the construction, combination 20 and arrangement of parts illustrated in the accompanying drawings which form a part hereof.

Figure 1 is a vertical sectional view practically through the center.

25 Fig. 2 is a bottom plan view.

Fig. 3 is a detail view on the line 3—3 of Fig. 2.

Like numbers refer to like parts in the views.

30 A bench table or convenient support 4 is shown in Fig. 1. To the support 4 a vise frame 5 is rigidly secured by bolts 4'. The frame 5 has a vertical, integral jaw 5' upon one end forming a joint with one side of the support 4. The lower part of the frame 5 has a downwardly faced, longitudinal worm-rack 6. The frame also has longitudinal guide tracks 7 suspended from its lower part below the worm-rack. A member 8 is provided, having parallel, longitudinal guide bars 9, arranged and adapted to 35 rest upon and slide along said guides 7. The bars 9 have a vertical, integral jaw 10 at their outer ends and a rectangular frame 40 11 secured upon and below the bars 9. Within the frame 11 is an operating rod 12. It has upon and near its outer end a sleeve 13 through which it extends in sliding engagement. The sleeve is transversely pivoted in and near the outer end of the frame 11 by pivots 14. Upon the outer end of the rod 12 a forked handle lever 15 is pivoted by a pivot 16. The handle lever 15 has flat sides which may engage the end of the sleeve 55 13. It also has a rounded lower end adapt-

ed to engage the end of the sleeve 13 in the nature of a cam and cause the rod 12 to move outwardly. At a convenient distance from the sleeve 13 a collar 17 is secured upon the rod 12. A coil spring 18 is placed about 60 the rod 12 between the sleeve 13 and collar 17, the respective ends of the spring engaging the sleeve and collar. The inner end of the rod 12 has a cone point 19. A block 20 is secured upon the inner end of the frame 65 11 and has a recess 21 adapted to receive the point 19. A sleeve 22 is rigidly secured upon the rod 12 near its inner end. The sleeve 22 has a worm-thread 23, adapted to engage the toothed rack 6. 70

It will now be seen that when the handle lever 15 is in the position indicated in Fig. 1, the inner end of the rod 12 rests in the recess 21 and the worm-thread 23 is in mesh with the toothed rack 6. Upon operating 75 the handle the rod 12 rotates and the jaw 10 is moved toward the jaw 5', or away from it, in the manner of a vise of common type. It will be further seen that when the handle 80 15 is lowered to the dotted position in Fig. 1, and the position shown in Fig. 2, the cam action of the end of the handle upon the sleeve 13 causes the opposing end of the rod 12 to withdraw from the recess 21, and the inner end of the rod may be dropped 85 slightly by a movement of the rod 12 on the sleeve pivots 14. This disengages the thread 23 from the worm-rack 6, and the frame supporting the lever may be moved quickly back and forth upon the guides to a desired 90 position. The handle is then raised to a vertical position and the lever operated as before for a close adjustment of the jaws. Upon raising the handle thus, the spring 18 actuates a forward movement of the rod 12 95 until its end engages the recess or socket 21 and the jaw 10 may be adjusted as before described.

It is contended that a vise of great strength is thus provided and also one which 100 allows operation to a close adjustment with a minimum of operative movements.

I claim—

105 A vise of the character described, having in combination, a frame securable to a convenient support and provided with a vertical jaw on its end, a downwardly faced worm-rack and longitudinal supporting guides suspended from said frame below the worm-rack, a member having parallel guide 110

bars adapted to rest upon and slide along said guides, said bars having a vertical jaw upon their outer ends positioned opposite the above frame jaw, a rectangular frame 11 secured to and below said bars, a sleeve pivoted within one end of said frame 11, a rod extending through said sleeve and into the frame, a worm-threaded collar secured upon and near the inner end of the rod in position 10 to engage the worm-rack, means in the end of the frame 11 to support the inner end of the rod, means to retain the rod in said support, a forked lever handle pivoted in the outer end of said rod, the lower ends of said

lever being cam formed in a manner to engage the adjacent sleeve and cause the withdrawal of the rod from its inner support when the lever is moved to a horizontal position, and at the same time to disengage the worm-thread from the worm-rack and allow 20 the outer jaw to be moved without engagement of the worm-thread with the worm-rack, substantially as described.

DAVID M. SMITH.
